Primary Examiner — Karen E Kearney*Assistant Examiner* — Debra A Callahan(74) *Attorney, Agent, or Firm* — Oblon, McClelland, Maier & Neustadt, L.L.P.(57) **CLAIM**

The ornamental design for an RFID reader/writer device, as shown and described.

DESCRIPTION

FIG. 1 is a front, top, and left side perspective view of an RFID reader/writer device;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines in the figures illustrate portions of the RFID reader/writer device that form no part of the claimed design.

1 Claim, 7 Drawing Sheets(56)
